DESIGN FOR A SLED

Howard J. Barrett, Philadelphia, Pa.

Application March 8, 1946, Serial No. 127,213

Term of patent 14 years

(Cl. D34—15)

To all whom it may concern:

Be it known that I, Howard J. Barrett, a citizen of the United States, residing at Philadelphia, in the county of Philadelphia and State of Pennsylvania, have invented a new, original, and ornamental Design for a Sled, of which the following is a specification, reference being had to the accompanying drawing, forming part thereof.

Fig. 1 is a top perspective view of a sled showing my new design.

Fig. 2 is a bottom perspective view of the same.

Fig. 3 is a side elevational view of the same.

I claim:

The ornamental design for a sled, as shown.

HOWARD J. BARRETT.
